(57) **CLAIM**

The ornamental design for the oxygen concentrator, as shown and described.

DESCRIPTION

FIG. 1 is a front perspective view of a first embodiment of the oxygen concentrator.

FIG. 2 is a rear perspective view of the oxygen concentrator in FIG. 1.

FIG. 3 is a front view of the oxygen concentrator in FIG. 1.

FIG. 4 is a rear view of the oxygen concentrator in FIG. 1.

FIG. 5 is a left side view of the oxygen concentrator in FIG. 1.

FIG. 6 is a right side view of the oxygen concentrator in FIG. 1.

FIG. 7 is a top view of the oxygen concentrator in FIG. 1.

FIG. 8 is a bottom view of the oxygen concentrator in FIG. 1.

FIG. 9 is a front perspective view of a second embodiment of the oxygen concentrator.

FIG. 10 is a rear perspective view of the oxygen concentrator in FIG. 9.

FIG. 11 is a front view of the oxygen concentrator in FIG. 9.

FIG. 12 is a rear view of the oxygen concentrator in FIG. 9.

FIG. 13 is a left side view of the oxygen concentrator in FIG. 9.

FIG. 14 is a right side view of the oxygen concentrator in FIG. 9.

FIG. 15 is a top view of the oxygen concentrator in FIG. 9; and,

FIG. 16 is a bottom view of the oxygen concentrator in FIG. 9.

The broken lines are for illustrative purposes only and form no part of the claimed design.
